UNITED STATES PATENT OFFICE.

JOSEPH D. ELDRIDGE AND WALTER W. GEHR, OF PHILADELPHIA, PENNSYLVANIA.

COLLAPSIBLE BARREL.

1,169,022.

Specification of Letters Patent. Patented Jan. 18, 1916.

Application filed November 7, 1914. Serial No. 870,842.

To all whom it may concern:

Be it known that we, JOSEPH D. ELDRIDGE and WALTER W. GEHR, citizens of the United States, residing at Philadelphia, in the county of Philadelphia and State of Pennsylvania, have invented new and useful Improvements in Collapsible Barrels, of which the following is a specification.

The present invention relates to improvements in the construction of barrels, hogsheads, etc.

In carrying out our invention it is our purpose to produce a barrel constructed of detachable sections which may be easily and quickly put together to form a complete barrel which shall be water and air tight and which sections may be also readily removed and collapsed to produce a comparatively small package either for shipment or storage.

It is also our purpose to provide a knock down barrel which shall embody the desirable features of simplicity in construction, cheapness and thorough efficiency.

With the above and other objects in view, the improvement resides in the construction, combination and arrangement of parts set forth in the following specification and falling within the scope of the appended claims.

In the drawings: Figure 1 is a perspective view of a barrel constructed in accordance with the present invention, Fig. 2 is a vertical transverse sectional view through the same, Fig. 3 is a horizontal section on the line 3—3 of Fig. 2, Fig. 4 is a similar section on the line 4—4 of Fig. 2, Fig. 5 is a detail perspective view of one of the heads looking toward the inner face thereof, Fig. 6 is a perspective view of one of the sections of the barrel, Fig. 7 is a detail enlarged sectional view approximately on the line 7—7 of Fig. 1, and Fig. 8 is a detail enlarged horizontal section illustrating two of the members or sections separated and about to be connected.

While our improved collapsible barrel is preferably constructed of metal, it is to be understood that the same may be formed of any other suitable or desirable material and also while, in the accompanying drawings, we have illustrated the barrel having its body constructed of three interlocking sections, we are not to be thus restricted in this particular, as any number of sections may be employed with equal efficiency.

In the drawings, the numeral 1 designates

the barrel proper and has its body formed of three curved sections 2, which, when connected, provide a body which is circular in cross section. Each of the sections, adjacent one of its longitudinal edges is bent inwardly upon itself as indicated by the numeral 3, and from thence bent outwardly, as indicated by the numeral 4, providing a substantially V-shaped groove or pocket 5, and the member 3 of which is spaced slightly but a suitable distance from the section proper.

The opposite longitudinal edge of the said section is bent inwardly at an angle, as indicated by the numeral 7, and the said angular portion has its end curved inwardly over the member 7 to provide a spring member 8 which contacts with the inner face of the said section which forces the member 7 away from the section proper, thus providing this end of the section with a suitable V-shaped tongue 9.

Each of the sections, opposite its pocket 5, and at suitable spaced intervals thereon has its outer face provided with bracket members 10, the same preferably including spaced ears between which is pivoted, as at 11, a threaded bolt 12, the said bolt having arranged thereon a nut 13, and the inner face of said nut is rounded or bulged outwardly, as indicated by the numeral 14. Each of the bolts 12 is provided with a stop member, preferably in the nature of a cotter pin 15 which is adapted to prevent the nut 13 from being accidentally removed from the bolt.

Each of the sections 2 opposite its tongue 9 is provided upon its outer face with oppositely projecting lugs 16, the same being preferably in the nature of slotted or bifurcated members to receive the bolt 12 when the latter is swung upon its pivot after the tongue 9 has been inserted within the resilient pocket 5. The outer face of each of the bifurcated lugs 16 is formed with a circular depression 17 against which the rounded inner face of the nut 14 is adapted to abut so that accidental outward swinging of the nut and bolt will be prevented.

In assembling the sections, a packing 18, preferably of some cheap absorbent paper is arranged within the V-shaped pocket and is of course contacted by the V-shaped tongue 9, and this packing strip will aid in preventing liquid from escaping from the barrel and also prevent moisture entering

the barrel. Ordinarily the strip or packing 18 is not necessary, as the spring engagement between the tongue 9 and the pocket 5 is sufficient to render the barrel water proof.

5 The sections 2 between the central and outer connecting member (that is the bolt and nut and the bifurcated lugs which receive the nuts and bolts) have arranged upon their outer faces cross sectionally rounded hoop members 19, each of which having one of its ends 20 reduced and projecting beyond each of the sections upon which the said member 19 is secured, the projection 20 providing a tongue which is inserted within the open end of the adjacent hoop section 19.

10 One or more of the sections 2 is provided, preferably between its hoops 19 with a bond in the nature of a threaded sleeve 21, the said sleeve having its inner face formed with an annular flange 22 and may be provided 15 with a packing or gasket of suitable compressible material and the said flange is secured to the section 2 by rivets or other suitable securing means. The threaded bore of the sleeve 21 is normally closed by a threaded plug 22'.

15 The numerals 23 designate the heads for the barrel. Each of these sections comprises a member having an annular flange 24, the 20 said flange adapted to snugly engage with the outer periphery of the barrel at the ends thereof, and the inner faces of each of the heads is provided with a gasket 25 which is held in place by a flat ring 26 that is secured 25 to the said head. One or both of the heads is provided with a bung opening, the same being in the nature of a flanged sleeve 27, the flange of the sleeve may be provided with a suitable gasket and secured to the said head 30 in any desired or preferred manner. The sleeve 27 may have its interior threaded and may be closed by a threaded plug 28. If desired, a wooden or compressible plug may be secured in the sleeve.

35 The flange of each of the heads at suitable spaced intervals have arranged upon their outer faces brackets 29 to which are pivotally secured bolts 30, the said bolts being provided with nuts 31 which have inner 40 conical or rounded faces 32, while a stop member, in the nature of a cotter pin 33, is passed through the bolt at the end thereof to retain the nut upon the bolt. The sections 2, adjacent the opposite ends thereof are 45 provided with bifurcated lugs 34, the inner faces of which being concaved, as at 35, and the bolts 30 are adapted to be swung between the arms provided by the bifurcations of the lugs, while the rounded faces of the nuts are 50 adapted to be received within the concaved 55 portions of the lugs 34.

60 From the above description, taken in connection with the accompanying drawings, the simplicity of the device as well as the advantages thereof will, it is thought, be per-

fectly apparent to those skilled in the art to which such invention appertains without further detailed description.

Having thus described the invention, what we claim is:

70 1. A barrel constructed of a plurality of similar metal sections, each of said sections having one of its longitudinal edges bent inwardly and extended outwardly to provide a substantially V-shaped pocket, the opposite longitudinal edge of each of the sections being bent inwardly at an angle and curved outwardly to contact with the inner face of the said section to provide a substantially V-shaped tongue and a spring therefor, the 75 said tongue of each of the sections being received within the pocket of the adjacent section, means for connecting the sections, said means adapted to force the tongues firmly within the pockets, and heads removably 80 connected with the barrel.

2. A barrel constructed of a plurality of similar metal sections, each of said sections having one of its longitudinal edges formed with a V-shaped pocket, the walls of which 85 being resilient, the opposite longitudinal edge of each of the said sections being provided with a V-shaped tongue, the walls of which are resilient, said tongue being further provided with a spring member which 90 forces the same from the sections, and the tongues of each section adapted to be received within the pocket of the adjacent section, means for removably connecting the 95 sections, said means adapted to compress the 100 tongues within the pocket, and removable heads for the barrel.

3. A metallic barrel comprising a plurality of segmental sections, each of said sections having one of its ends bent inwardly 105 and extending outwardly to provide a substantially V-shaped groove which extends the entire length of the said section, the opposite end of each of the sections being bent angularly to provide a V-shaped tongue, the 110 inner end of which being curved inwardly of the V-shaped tongue to provide a spring between the members comprising the tongue and the said tongue and spring extending the entire longitudinal length of the section, 115 and means arranged upon one of the sections co-acting with the adjacent section for forcing the spring tongue of one of the said sections into frictional engagement with the pocket of the co-acting section.

120 4. A metallic barrel comprising a plurality of segmental sections, each of said sections having one of its ends bent inwardly and extending outwardly to provide a substantially V-shaped groove which extends 125 the entire length of the said section, the opposite end of each of the sections being bent angularly to provide a V-shaped tongue, the inner end of which being curved inwardly of the V-shaped tongue to provide a spring 130

between the members comprising the tongue and the said tongue and spring extending the entire longitudinal length of the section and means for locking the sections, said 5 means including swinging members having adjustable elements arranged adjacent the end of each of the sections and spaced lug members adjacent the opposite end of each of said sections and adapted to receive the 10 swinging member of the adjacent section to

be contacted by the adjustable element thereon.

In testimony whereof we affix our signatures in presence of two witnesses.
